Asaiah Penning

The Schedule referred to in these Letters Patent contains the original part of the same containing a description in the words of the said Asaiah Penning, himself, of his improvements in the Steam Engine and other Machinery.

First construct a common Cylinder with a flange at each end projecting cylindrically about one inch. To this exterior adapt a piston as usual. A second cylinder must then be formed, large enough to contain or inclose the first. The outer and inner cylinders must be distant from each other about one inch, and the former must at both ends be firmly fastened to the underside of the flanges projecting from the latter.

Place one or more of these double cylinders in or over the fire of the furnace so as to permit the piston when in operation to act upon the fire beneath, and cause the flame and smoke to regularly to ascend, descend with it, and the smoke to be consumed without escaping from the furnace. The vacant space between the double cylinders receive the water or steam through a pipe which connects the cylinders and boiler. From the vacuum thus formed between the outer and inner cylinders, the steam passes through the small pipe and valves into the chamber of the inner cylinder on the top of the piston; the steam thus introduced causes the piston to descend in a regular movement. The working gear attached to the piston may be the same as is used in ordinary steam engines, or may be varied at the discretion of the designer. The position of the cylinders may also be changed at the pleasure of the constructor. One cylinder disposed in the place of the furnace will equally serve to circulate the heat. They may also be placed in the furnace without an outer case and worked with a double stroke, according to the common practice. Second construct a flue to your

rest of many cylinders best communicating with each other by pipes. Each cylinder is formed by two iron plates, two feet square and one quarter of an inch thick. Join the plates by an iron band about one inch wide a quarter in width and half an inch thick. The edges of each plate should be somewhat thickened, and then firmly welded to the edges of the iron band which is placed between them on all sides, and by retaining them apart forms the vacuum for that division of the boiler. Any number of similar cylinders may be added to constitute the boiler, taking care to connect them by pipes secured near the edges. The shape and dimensions of each cylinder may be varied, of thought convenient, and instead of the connecting band, the plates may be united with a space between them of about one inch, by clinching their edges. Each cylinder may be provided with a spring safety valve, or others may be substituted, and the water may be introduced into the boiler either at the top or elsewhere. Third. To fit the piston of a cylinder to the cylinder, and keep it tight, form a ring at the lower extremity of the piston, by a living lathe, so as to fit close to the inside of the cylinder. Then from one side of the piston, ring out out a piece of a triangular shape, having its vertex at edge of the ring, and the base of the triangle receding towards its centre. In the opening thus formed fit a spring wedge firmly with its sharp edge against the side of the cylinder. By the pressure of the spring upon the wedge, the latter causes to expand the sides of the ring upon which it acts, and thus by pressing it tighter to the inner surface of the cylinder obviates the inconvenience arising from the room and leas at the outer edge of the ring. The spring wedge is kept from in its position by corresponding plates placed above and below the centre plate, and the centre plate has an additional

lional plate, within it, with one straight side to bind the spring wedge, and pressing against it; these when thus joined form the lower extremity of the piston.

Fourth. To give greater security to the shafts of steam engines, water wheels, and other machinery, construct a coupling box in the usual form, except the ends on the face of each part of the box. There must be made to incline somewhat to a point, in imitation of a wedge; acting upon the movable section of the coupling box is a spiral spring fixed around the shaft, and having its spiral extremity resting against a collar, either projecting from the shaft or fixed to it, so as to change its position and of necessity increases or diminishes the power of the spring. When the shaft is in motion, by the regular power of the engine, the pressure of the spring keeps the boxes mated; but if the water wheel or steam boiler or other machinery should strike any solid substance, and meet with a resistance greater than the power applied, the coupling box by means of the sliding section and spiral spring diminishes of itself, and will continue until such resistance ceases, when they again mate by the power of the spring. The peculiar advantages of the preceding improvements, consist, as follows: First, by placing the piston and cylinder in the furnace, the fire drives up the heat and fire and expands the steam more readily; It causes the fire to burn more briskly; consumes the smoke, and also saves fuel.

Secondly, the bodies with straight sides are stronger, more secure and more easily made. Thirdly, the piston, acting with the spring wedge, is more simple and cheaper than any other, and answers better for packing of pistons. Fourth. The coupling box with its spring and slides, prevents the shaft and machinery from being

king, when any sudden shock or violent resistance is
encountered; for the same reason the mechanism may
be made much lighter than with the box used in common,
on account of these advantages therefore. Retaining the
exclusive privilege, and a patent for the form proceeding
influence, securing to me the sole right of construct-
ing, using and vending the same.

DEPARTMENT OF THE INTERIOR,

United States Patent Office,

Washington, D. C., , 189

SIR:

The printed *Official Catalog* of Patent No. *5,001,619* is
now exhausted.

As soon as printed a copy will be mailed you to complete your order.

By direction of the Commissioner:

Very respectfully,

Chief Clerk.
